(57) **CLAIM**

The ornamental design for a camcorder, as shown and described.

DESCRIPTION

FIG. 1 is a front perspective view of a camcorder;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom view thereof;

FIG. 9 is a front perspective view thereof showing the article with its monitor panel opened; and,

FIG. 10 is a rear perspective view thereof showing the article with its monitor panel opened.

Those portions of the drawings shown in broken lines are unclaimed subject matter and form no part of the claimed design or of a specified embodiment thereof.
